UNITED STATES PATENT OFFICE.

FREDRICK MENZENHAUER, OF JERSEY CITY, NEW JERSEY.

METALLOPHONE-ZITHER.

SPECIFICATION forming part of Letters Patent No. 546,174, dated September 10, 1895.

Application filed November 24, 1894. Serial No. 529,836. (No model.)

To all whom it may concern:

Be it known that I, FREDRICK MENZENHAUER, a citizen of the United States, residing at Jersey City, in the county of Hudson and 5 State of New Jersey, have invented certain new and useful Improvements in Metallophone-Zithers, of which the following is a specification.

This invention relates to a new musical instrument that is formed of a combination of the well-known zither with a so-called "metallophone," or instrument in which musical sounds are produced by means of a number of different-toned metallic bars or plates when 10 they are struck by a suitable hammer, whereby an instrument is obtained that may be easily played with little practice, so that it can be placed within the reach of children of different ages, but which can also be furnished on 15 a larger and more extended scale, so as to become an instrument by which a better class of music can be produced in the hands of a skilled performer, especially as the related sounds of the metallic bars or plates and the 20 strings can be blended with each other in new and attractive effects; and the invention consists of a musical instrument or metallophone-zither which comprises a sounding-board having a longitudinal opening, raised portions at 25 each side of the opening, and metallic bars or plates supported on the raised portions of the sounding-board, and a number of groups of strings on the sounding-board extending transversely of the metallic bars in juxtaposition 30 to the ends of the same, while the strings of each group are tuned to the intervals of separate harmonic chords of the bars or plates, as hereinafter more fully described, and then 35 specified in the claim.

40 In the accompanying drawings, Figure 1 represents a top view of my improved musical instrument or metallophone-zither. Fig. 2 is a vertical transverse section of the same on line 2 2, Fig. 1; and Fig. 3 is a detail transverse section on line 3 3, Fig. 1, showing the metallophone on a larger scale.

Similar letters of reference indicate corresponding parts.

Referring to the drawings, A represents the 50 sounding-board, which is made in the form of that of a zither, and which can be made of any suitable size and finish, according as to

whether the instrument is to be used as an instrument for children or for a skilled performer. At one side of the sounding-board A 55 is arranged a metallophone B, of the well-known construction, said metallophone being composed of a number of metallic bars or plates b, that are tuned according to the ordinary scale. The metallophone is supported 60 upon strips E, forming raised portions located at each side of an opening A', extending longitudinally of the sounding-board, so that the tones produced by the striking of the bars or plates composing the metallophone will be 65 clear and distinct. Along the other side of the sounding-board and parallel with the metallophone, so as to extend transversely of the metallic bars forming parts of the metallophone, are arranged a number of groups of 70 strings—namely, C C' C²—which are tuned to the intervals of separate harmonic chords for the different bars or plates b of the metallophone B, each group being composed of a bass string and additional strings tuned 75 harmonically with the bass string.

When playing the instrument, the hammer for striking the bars or plates of the metallophone is taken in one hand, the melody being produced by striking in succession the 80 bars of the metallophone, while the accompaniment is produced by the thumb passing over that group of strings that is tuned in harmonic chord with the bar or plate struck by the hammer. In this manner the melody 85 is played on the metallophone, while the accompaniment is given by sounding of corresponding groups of strings, whereby a very novel and effective musical instrument is obtained, that can be made on a small scale for 90 children, while when built on a large scale it forms an instrument for the skilled performer that is far superior to the ordinary metallophone, tumblerophone, or musical glasses, and similar instruments, as the same permits 95 the playing of a better class of music and furnishes a very interesting and pleasing instrument.

It is evident that instead of a metallophone a xylophone may be mounted on the sounding-board, and that for the bars resonant tubes may be substituted without departing from the scope and spirit of the invention.

Having thus described my invention, I

claim as new and desire to secure by Letters Patent—

A musical-instrument or metallophone-zither, consisting of a sounding-board having 5 a longitudinal opening, raised portions each side of said opening and metallic bars or plates supported on the raised portions of the sounding-board, and a number of groups of strings on the sounding-board extending 10 transversely of the metallic-bars, in juxtaposition to the ends of the same, the strings

of each group being tuned to the intervals of separate harmonic chords of the bars or plates of the metallophone, substantially as set forth.

In testimony that I claim the foregoing as 15 my invention I have signed my name in presence of two subscribing witnesses.

FREDRICK MENZENIAUER.
